CLAIM

The ornamental design for a defibrillator with retractable hooks, as shown and described.

DESCRIPTION

FIG. 1 is a perspective view of a defibrillator with retractable hooks, showing our new design, with the broken line showing of the defibrillator paddles, lead wires, plug and electrical connection sites being for illustrative purposes only and forming no part of the claimed design;

FIG. 2 is a front elevational view thereof;

FIG. 3 is a left side elevational view thereof, with the retractable hooks shown in extended position;

FIG. 4 is a right side elevational view thereof;

FIG. 5 is a right side elevational view thereof, with the retractable hooks shown in retracted position;

FIG. 6 is a rear elevational view thereof;

FIG. 7 is a top plan view thereof; and,

FIG. 8 is a bottom plan view thereof.
